(57) **CLAIM**

The ornamental design for an optical scanner, as shown and described.

DESCRIPTION

FIG. 1 is a perspective view of an optical scanner according to the present invention;

FIG. 2 is a front view of the optical scanner of FIG. 1;
FIG. 3 is a back view of the optical scanner of FIG. 1;
FIG. 4 is a left side view of the optical scanner of FIG. 1;
FIG. 5 is a right side view of the optical scanner of FIG. 1;
FIG. 6 is a top view of the optical scanner of FIG. 1; and,
FIG. 7 is a bottom view of the optical scanner of FIG. 1.
The portions of the optical scanner shown in broken lines
form no part of the claimed design.

1 Claim, 4 Drawing Sheets
